United States Patent Office

Des. 208,254
Patented Aug. 8, 1967

208,254

SPOTWELDER

John W. Ryan, Bel Air, and Gerald W. Schmidt, Tarzana, Calif., assignors to Mattel, Inc., a corporation of California

Filed Jan. 20, 1966, Ser. No. 691

Term of patent 14 years

(Cl. D26—1)

FIG. 1 is a perspective view of a spotwelder showing our new design;

FIG. 2 is a rear end elevational view of the design;

FIG. 3 is a left-hand side elevational view of the design; and

FIG. 4 is a plan view of the design.

The dominant features of our new design are shown in solid lines.

We claim:

The ornamental design for a spotwelder, as shown and described.
